(57) **CLAIM**

The ornamental design for a cable guide projection with boss, as shown.

DESCRIPTION

FIG. 1 is a top isometric view of the design for a cable guide projection with boss in accordance with a preferred embodiment of the present invention;

FIG. 2 is a bottom isometric view of the cable guide projection with boss of FIG. 1;

FIG. 3 is a top view of the cable guide projection with boss of FIG. 1;

FIG. 4 is a bottom view of the cable guide projection with boss of FIG. 1;

FIG. 5 is a front view of the cable guide projection with boss of FIG. 1;

FIG. 6 is a right side view of the cable guide projection with boss of FIG. 1; and,

FIG. 7 is a left side view of the cable guide projection with boss of FIG. 1.

Portions of the design shown in broken lines form no part of the claimed design.

1 Claim, 5 Drawing Sheets
